FLEXIBLE ARCH SUPPORT

Application filed April 20, 1932. Serial No. 606,452.

This invention relates to arch supports for supporting and correcting fallen or deformed arches of the human foot, and has for an object the provision of an arch support which is arranged in superposed position on the insole of a shoe and which is adjustable in elevation above the sole of the shoe to correctly support the arch of the wearer and to cause the arches of the wearer to be returned to their normal condition.

Another object of the invention is the provision of an arch-supporting plate which is adjustable in elevation above the insole of the shoe and which is also flexible so that when the plate is adjusted to the elevation desired under the several arches of the foot the plate will conform to the natural shape of the instep of the wearer.

Still another object of the invention is the provision of a longitudinally-arched supporting plate rigidly connected laterally to the sole of the shoe in the region of the instep and unsecured at its ends whereby it is free to flex with the movement of the foot of the wearer.

The invention also contemplates an arch-supporting plate having a curved forward portion extending under the ball of the foot, which forward portion is slotted inwardly toward the region of the ball of the foot to provide a flexible extension which will give the required support yet will be comfortable to the wearer.

The invention is shown in the accompanying drawing, in which

Figure 1 is a top plan view of a shoe with a portion of the upper removed to show the arch-supporting plate in position therein and the adjustable means for supporting the plate in dotted lines;

Fig. 2 is a longitudinal sectional view on the line 2—2 of Fig. 1;

Fig. 3 is a plan view of the arch-supporting plate;

Fig. 4 is a plan view of the curved plate which underlies the arch-supporting plate in the region of the ball of the foot;

Fig. 5 is a sectional view on the line 5—5 of Fig. 4;

Fig. 6 is a top plan view of the adjustable

sleeve member which supports the arch-supporting plate and the curved plate in position under the ball of the foot;

Fig. 7 is a cross-sectional view on the line 7—7 of Fig. 6.

In carrying out the invention, an arch-supporting plate 10 is arranged in superposed position on the insole of a shoe. This plate is coextensive with the sole of the shoe in the region of the instep and is made of a thin flexible spring metal which is shaped to conform to the natural shape of the instep of a normal foot but which may be flexed to suit particular conditions by making adjustments at the points of attachment 60 with the shoe. As shown in the drawing, the said plate is applied to a right shoe, but it is to be understood that the construction is the same for a shoe to be worn on the left foot, the plate for the left shoe being curved to conform to the last of a left shoe. The said plate is arched longitudinally, the forward end extending a short distance beyond the ball of the foot and is supported by an adjustable means arranged in the sole of the shoe substantially centrally under the ball of the foot. The rearward end of the plate rests on the sole of the shoe adjacent the heel, and between these points of support the plate is adjustable in elevation toward and from 65 the sole of the shoe at a plurality of points on a transverse line in the region of the instep under the longitudinal arches.

The side edges 11 and 12 of the said plate are curved to conform to the last of the shoe 85 and, as shown in Fig. 1, the edge 12 is provided with a raised lip 13 which gives support to the side of the foot in the region of the instep. The forward end of this plate which extends under the ball of the foot, is curved to define an arc of substantially a half-circle, and on each side of the said curved end the forward edge of the plate extends laterally to the side edges 11 and 12. The said curved end is preferably slotted by alternate long and short length slots 14 and 15 which radiate outwardly substantially from a point 90 which underlies the ball of the foot. These slots may be of irregular formation, as shown in Fig. 3, or they may be formed 95

straight if so desired. Preferably, each of the said slots terminates at a small circular hole 16 in the plate to prevent the plate rupturing beyond the said opening.

To secure the plate 10 in position on the insole of the shoe and to provide means for adjusting the height of the same above the insole, the said plate, adjacent each side edge 11 and 12 thereof, is rigidly affixed to a flange 17 of an interiorly-threaded tubular member 18, which latter member is slidably mounted in a guide sleeve 19 arranged in an opening in the sole of the shoe. A screw 20 having a flanged head 21 is positioned against one end of the guide sleeve 19 and with its threaded shank 22 engaging the interior threaded opening of the tubular member 18, whereby turning of the said screw in one direction will cause the upper end of the tubular member 18 and the said plate affixed thereto to be progressively raised above the insole of the shoe, while turning the said screw in the opposite direction will cause the said member and the plate affixed thereto to be drawn down toward the insole of the shoe. The outer end of the screw 20 projects through an opening 23 in an outer plate 24, which plate is connected by rivets 25 to the flange 26 of the said guide sleeve 19, thereby securing the said sleeve in position in the opening in the shoe sole.

A similar adjusting means is arranged in an opening in the shoe sole, substantially centrally of the sole, and which underlies the ball of the foot as hereinbefore described. This adjusting means constitutes a support for the forward end of the said plate, and provides means by which the plate may be elevated to the position desired, above the shoe sole. Instead of being affixed to this adjusting means, the forward portion of the said plate is freely supported upon a leather pad secured to an oval-shaped plate 27 which latter plate is adapted to be supported in various positions upon a flange 28 of an interiorly-threaded tubular member 29. This tubular member is slidably mounted in a guide sleeve 30 similar to the construction of the guide sleeve 19. The plate 27 is provided with a plurality of slots 31 extending inwardly from the outer edge thereof to provide a flexible rim portion which will freely bend when weight is applied thereupon. The plate also is provided with a series of circular openings 32 arranged in longitudinal and transverse rows in the central portion thereof. Any one of these openings is adapted to be engaged by a stud 33 arranged at the center of the flange 28 of the tubular member 29, to hold the said plate in the desired position thereupon, and when in such position the said plate may be secured to the flange 28 by rivets or other securing means engaging the openings therein.

Preferably a leather pad or covering 34 is

arranged between the plate 27 and the under side of the forward end of the plate 10. This covering extends forwardly of the said plate and provides a cushioned surface for the forward end of the plate 10. Supported in this manner the forward end of the said plate is free to flex or bend when the weight of the wearer is imposed thereupon.

The said adjusting means under the forward end of the said plate 10 is provided with a screw 35, similar to the screw 20, for regulating the height of the end of the plate above the sole of the shoe. A leather insole 36 coextensive with the sole of the shoe may be arranged in superposed position upon the plate 10, as shown in Fig. 2. This insole prevents direct contact of the foot of the wearer with the metallic plate 10.

What is claimed is:

1. The combination of a shoe and an arch support including a longitudinally-arched plate arranged in the inside of the shoe and extending from the heel of the shoe forwardly to underlie the ball of the foot, the forward end of said plate being provided with a plurality of spaced slots to form a flexible forward end portion, and adjustable means arranged in the sole of the shoe under the forward end of the said plate for regulating the height of the flexible end portion of the said plate above the sole of the shoe.

2. The combination of a shoe and an arch support including a metal plate arranged on the inside of the shoe and extending from the heel of the shoe forwardly to underlie the ball of the foot, the forward end of said plate being curved to form substantially the arc of a half-circle and being provided with a plurality of spaced slots to form a flexible forward end portion, and adjustable means arranged in the sole of the shoe under the forward end of the said plate for regulating the height of the flexible end portion of the said plate above the sole of the shoe.

3. The combination of a shoe and an arch support including a longitudinally-arched plate arranged on the inside of the shoe and extending from the forward end of the heel of the shoe forwardly to underlie the ball of the foot, said plate having its side edge shaped to conform to the last of the shoe and its forward end slotted to form a flexible end portion which underlies the ball of the foot, adjustable means secured to the sole of the shoe under the arch of said plate, and independent adjustable means under the said slotted end for adjusting the height of the arch of the plate and the said flexible end portion thereof.
